UNITED STATES PATENT OFFICE.

ALEXANDER BURTON RANDALL, OF PHILADELPHIA, PENNSYLVANIA.

AMPHITHEATER OR STADIUM.

Application filed August 17, 1922. Serial No. 582,402.

To all whom it may concern:

Be it known that I, ALEXANDER B. RANDALL, a citizen of the United States, residing at Philadelphia, in the county of Philadelphia, State of Pennsylvania, have invented certain new and useful Improvements in Amphitheaters or Stadiums; and I do hereby declare the following to be a full, clear, and exact description of the invention, such as will enable others skilled in the art to which it appertains to make and use the same.

The invention relates to a novel form of amphitheater or stadium for the exhibition of athletic games, field sports, pageants, theatrical displays and the like, and has for its object to provide a novel form of construction of edifice of the character indicated, which will provide seating areas for the audience in which the major portion, approximately eighty per cent, of the spectators will be disposed and located so as to be enabled to view the field transversely, and the minor portion of the seats, approximately twenty per cent, only, will face substantially up and down the field. The novel type of amphitheater or stadium also provides means for expeditiously disposing of large audiences entering and leaving the building, and greatly facilitates the orderly seating of the spectators by providing large concourse halls within the building structure connected with the seating area by numerous entrances and aisles, and with the exterior of the building by entrances and exits opening either directly upon an encircling esplanade, or connected to the latter by means of spacious ramps or stairways, capable of accommodating capacity audiences.

To these ends, the invention comprises a generally ring-shaped structure having an inclined deck included between the inner and outer walls, constituting the seating area, sloping toward the substantially ellipsoidal field, the deck aforesaid gradually increasing in elevation and width between the longitudinal and transverse axes of the field, so that the major portions of the inclined deck or seating area will be disposed along the length of the field and a relatively small proportion of the seating area will be disposed at the ends of the field.

The invention is illustrated in the accompanying drawings, in which,

Fig. 1 is a perspective view, more or less diagrammatic, of the amphitheater or stadium;

Fig. 2 is a view looking down on the structure, one-half being shown in full plan and the other half in horizontal section;

Fig. 3 is a transverse section on line 3-3 of Fig. 2;

Fig. 4 is a longitudinal section on line 4-4 of Fig. 2.

In the construction of amphitheaters, stadia and similar structures, involving the disposition of banked or inclined tiers of seats around a central field, which latter is usually ellipsoidal in form, it has been customary to erect the structure supporting the seating areas to conform generally to the shape of the field, either completely surrounding the latter, or surrounding all but one end of the field, which latter is left open. According to the prevailing practice, which has been in vogue since approximately the beginning of the Christian era, the building structure conformed generally to the shape of the field, and included outer walls of substantially uniform height and inner walls, marking the boundary of the field, also of substantially uniform but lesser height than the outer walls, with an inclined deck or seating area, disposed between the inner and outer walls. As a result of this more or less standard type of construction, practically one-half of the seats faced transversely of the central field, and the other half of the seats faced longitudinally of the field, when the building was generally ring-shaped, either ellipsoidal or circular. When the structure was made U-shaped or on the so-called "hairpin plan," with one end open, the seating area represented by the omitted section of the structure was lost. In addition to the unfavorable disposition of the seating areas located opposite the ends of the field, the entire seating area of the structure was necessarily limited by the form of the building. In modern times, there has been evidenced a growing demand for stadia to accommodate very large audiences, which has resulted in the erection of larger struc-

tures, which, however, did not overcome the salient objections to the dispositions of a very large proportion of the audience, which was forced to view the field lengthwise, so 5 that many of the elements of the exhibition or play were confused. In other words, the larger the structure and the greater the seating area provided, the more numerous were the spectators who were obliged to occupy 10 unfavorable seats facing in the general direction of the longitudinal axis of the central field. As a general rule, the modern sports and games, such as football, lacrosse, and field and track athletics, involve action of 15 the participants which takes place generally lengthwise of the enclosed field, which is almost universally ellipsoidal in form, so that a full and satisfactory observation of all of the elements of the play or contest can only 20 be had when the observer has a clear view transversely of the field.

As indicated, the present invention provides a novel form of amphitheater or stadium, which may be constructed to accommodate 25 very large audiences without unduly enlarging the dimensions of the structure, but which will enable the major portion of the audience, approximating eighty per cent thereof, to occupy favorable 30 seats facing transversely of the field. A typical construction to effect these desirable objects is illustrated in the accompanying drawings, as erected upon an area of hilly or rolling ground, which, under ordinary 35 circumstances, would present serious difficulties in the disposition and arrangement of the approaches to the structure to ensure the expeditious, orderly and efficient handling of large audiences entering and 40 leaving the building, but in the present case, illustrates the adaptability of the invention to any desired locality, without unduly increasing the cost of construction, and without detriment to the comfort and convenience 45 of the audience in entering and leaving the structure.

Referring to the drawings, it will be noted that the central field is longer than it is wide, to conform to the general requirements 50 of an athletic field to accommodate football games, track and athletic meets and similar sports or games, and is completely surrounded and enclosed by the building structure, which latter comprises a central section 1 bounded on its inner periphery by a wall 55 or parapet 3 of substantially uniform height, which surrounds and defines a central field, and bounded on its outer periphery by an encircling aisle 6, which is at a uniform elevation throughout its extent, the 60 space between the inner wall 3 and the elevated aisle 6 being occupied by a deck or covering 7 constituting part of the seating area, which rises uniformly from the lower 65 level adjacent the inner wall 1 to the upper

level of the aisle 6. It will be noted that this portion of the structure conforms substantially to the general plan and arrangement of amphitheaters or stadia, as heretofore designed, with the inclined deck or 70 seating area extending upwardly and outwardly from the marginal edges of the central field to a uniform height at all points in its outer marginal limits, the general contour of the structure being that of a concave 75 ellipsoidal bowl.

The central section 1 of the structure is surrounded by an outer section 2, the outer defining wall 4 of which gradually increases in height between the longitudinal and transverse axes of the enclosed field, said wall constituting the outer support for an inclined deck section 8 extending from the outer marginal limits of the section 1 toward the top of the outer wall 4, so that the said deck section 8 also gradually increases in elevation and width between the longitudinal and transverse axes of the field. In the particular exemplification of the invention, the outer defining wall of the stadium is substantially circular in plan, but it will be understood that it is not limited to this particular geometrical form, but may be given the form of any other desired regular closed curve. 95

It will be seen, therefore, that the construction as described involves an inner defining wall of substantially uniform height surrounding the central field, and an outer defining wall which gradually increases in height between the longitudinal and transverse axes of the field, the two walls defining the limits of the inclined deck or seating area, which also gradually increases in elevation and width in each quarter section of 100 the structure between the longitudinal and transverse axes of the field, so that by far the larger proportion of the seating area will be disposed laterally of and, therefore, 105 facing toward the longer or longitudinal dimension of the playing field. 110

Preferably, the building is surrounded by a wide walk or esplanade 14, which gives entrance to and exit from portals in the surrounding wall, which establish communication either directly, or by way of ramps or stairways, with the relatively large concourses or halls 15 located under the deck portions 8 of the outer section 2 of the structure, the floor of the concourses or 120 circulating areas 15 preferably being located on a level with the aisle 6 surrounding the inner section 1, so that the larger proportions of the audience may make entrance and exit through the circulating areas at the common 125 level represented by the aisle 6 between the inner and outer sections of the structure. It will be understood that each of the decks or seating areas will be divided into sections by cross-aisles such as 10 in section 1, 130

and 11 in section 2. The aisles 10 connect with a common aisle 5, surrounding the playing field inside of the inner wall 3, and with the aisle 6 which separates sections 1 and 2. Portals 9 opening from the level of the concourse sections 15 give access immediately to aisle 6, so that an expeditious distribution of the audience may be made in any and all seating sections directly from the concourses. The aisles 11 connect with aisle 6 between the two sections and with an encircling aisle 6' located at the upper marginal edge of the deck section 8 and within the outer wall 4. Under certain circumstances, it may be found expedient to permit portions of the audience to enter and leave the seating areas by way of the central field, and passageways, ramps or stairways passing through the lower part of the structure. To permit this condition to maintain, the lower aisle or passageway 5 surrounding the field connects at various points with stairways or short flights of steps formed in or adjacent to the wall 3 and preferably opposite the lower ends of certain of the cross-aisles 10, which will permit members of the audience desiring to do so to pass directly onto the playing field and thence through lower passageways, such, for example, as 20, shown in Fig. 3, to the exit. Further reference to the construction illustrated in Fig. 3 shows an effective arrangement of ramps, such as 16, admitting the passage of the patrons directly from a main entrance to the concourse hall 15, whence they may pass directly to the particular seating section to which they are assigned, by selecting the proper portals 9. By reference to Fig. 1, it will be noted that entrance and exit may be effected expeditiously and without dangerous congestion at practically all points in the exterior wall of the structure, and as the majority of the spectators necessarily pass through the concourse sections 15, and thence through portals 9 to the aisle 6 separating the upper and lower sections, it will be obvious that the audience may be properly distributed with a minimum expenditure of time, effort and service.

Preferably a large open portal is provided at one end of the structure, as indicated at 30, on a level with the esplanade 14 and the aisle 6, which not only adds to the general aesthetic effect of the structure and permits a general view of the entire interior of the amphitheater or stadium, to those entering by this portal, but also serves to relieve any tendency toward congestion which would be likely to occur at the main portal in any event. It will be noted that this spacious portal is provided at a sacrifice of only a relatively small portion of the seating area or deck space at one of the narrow ends of the field, which, as indicated

is the least desirable location for observing the modern games and contests.

The structure is provided with relatively large portals 12 and 13 opposite the narrow ends of the field to afford ready entrance and exit for the participants in the games or sports, and those portions of the audience entering at the level of the field.

As indicated, the field is limited in its area, in constructions of this kind, to accommodate such games as football, lacrosse, and the ordinary track and field sports, so that, as a rule, the field is not large enough to accommodate a straightaway track of over 100 yards, for races requiring a track of this particular character. In order, therefore, to extend the straightaway section of the track, provision may be made for removing a section of the structure at the point marked "X" in Fig. 2. This may be effected by erecting that portion of the general structure in line with the track extension in so-called "knock-down form", so that said section may be entirely removed, leaving the track extension open. This removable section of the stand may be constructed of removable elements of metal or wood, capable of being readily removed and replaced.

It will be understood, of course, that the structure may be built of any suitable materials, but is specially well adapted to the employment of the modern type of reinforced concrete construction, or a combination of concrete and steel which will best serve the requirements as to strength, durability and aesthetic effect. It will be particularly noted that such a construction involves many halls, rooms and compartments within the body thereof, in addition to the relatively large concourses or assembly halls under the lateral sections 8 of the deck or seating area, which may be advantageously employed as club rooms, locker rooms, baths, storage spaces and the like. It will also be obvious that many changes or variations may be made in the structure as a whole without departing from the broad invention involved, namely, the construction and arrangement of the amphitheater or stadium so that the major portion of the seating area faces transversely of the central field.

What I claim is:

1. An amphitheater or stadium having an inclined seating area surrounding the central field, the outer peripheral boundary of said area increasing in elevation from the longitudinal to the transverse axis of the field, and said area gradually increasing from a minimum width along the longitudinal axis of the field to a maximum width along the transverse axis of the field.

2. An amphitheater or stadium comprising a substantially ring-shaped structure

having an inclined seating area between the inner and outer walls thereof, said area having its minimum width and outer peripheral elevation on the longitudinal axis of the field 5 and gradually increasing in width and elevation toward the transverse axis of the field.

3. An amphitheater or stadium comprising a substantially ring-shaped structure 10 having an inner defining wall of substantially uniform height, an outer defining wall that gradually increases in height from the longitudinal to the transverse axis of the field, and an inclined deck connecting said 15 walls near the tops thereof.

4. An amphitheater or stadium comprising a substantially ring-shaped structure having an inclined deck or seating area included between the inner and outer boundaries of said structure, said deck or seating 20 area having its minimum width and outer peripheral elevation on the longitudinal axis of the field and gradually increasing in width and elevation toward the transverse 25 axis of the field, gradually increasing in elevation and width between the longitudinal and transverse axes of the field.

5. An amphitheater or stadium comprising a substantially ring-shaped structure 30 having its inner defining wall substantially ellipsoidal and its outer defining wall substantially circular, and an inclined deck connecting the walls near the tops thereof, the

outer wall gradually increasing in elevation from the longitudinal to the transverse axis 35 of the structure.

6. An amphitheater or stadium comprising a substantially ring-shaped structure having an inner defining wall of substantially uniform height, an outer defining wall 40 that gradually increases in height from the longitudinal to the transverse axis of the field, an inclined deck connecting said walls near the tops thereof, aisles extending 45 around the deck at the bottom, top and intermediate sections, and cross-aisles connecting the curvilinear aisles.

7. An amphitheater or stadium comprising a substantially ring-shaped structure having an inner defining wall of substantially uniform height, an outer defining wall that gradually increases in height from the longitudinal to the transverse axis of the field, an inclined deck connecting said walls near the tops thereof, aisles extending 50 around the deck at the bottom, top and intermediate sections, cross-aisles connecting 55 the curvilinear aisles, concourse halls below the outer deck sections, and portals connecting said halls with the exterior of the structure and with the intermediate curvilinear aisle.

In testimony whereof I affix my signature.

ALEXANDER BURTON RANDALL.
